UNITED STATES PATENT OFFICE.

MILFORD BERRIAN FERGUSON AND EDWARD HAAS, OF BROOKLYN, NEW YORK.

WRAPPING MECHANISM FOR CANDY.

1,329,236.

Specification of Letters Patent. Patented Jan. 27, 1920.

Application filed July 6, 1918. Serial No. 243,604.

To all whom it may concern:

Be it known that we, MILFORD B. FERGUSON and EDWARD HAAS, citizens of the United States, and residents of the city of New York, borough of Brooklyn, in the county of Kings and State of New York, have invented a new and Improved Wrapping Mechanism for Candy, of which the following is a full, clear, and exact description.

Our invention relates to wrapping mechanisms for candies, particularly designed for wrapping cylindrical or prismatically-shaped candies.

An object of the invention is to provide a simple and efficient mechanism with which candies can be quickly and neatly wrapped.

Another object of the invention is to provide a candy-wrapping mechanism which can form part of a machine for labeling, packing and otherwise manipulating candies after they have been wrapped.

With the above and other objects in view, the nature of which will more fully appear as the description proceeds, the invention consists in the novel construction, combination and arrangement of parts as herein fully described, illustrated and claimed.

In the accompanying drawings, forming part of the application, similar characters of reference indicate corresponding parts in all the views.

Figure 1 is a diagrammatic side elevation of the wrapping mechanism;

Fig. 2 is a similar fragmentary elevation of the mechanism showing a different position of the candy feed and paper cutting elements;

Fig. 3 is a similar elevation to that shown in Fig. 1 with a further change in position of the various elements of the mechanism;

Fig. 4 is a top plan view of the mechanism as shown in Fig. 3, certain parts being shown in section to illustrate the details of construction;

Fig. 5 is an elevation of the spinning mechanism and the means for actuating the same;

Fig. 6 is a section through the mechanism on line 6—6, Fig. 5;

Fig. 7 is a diagrammatic elevation of the spinning mechanism and track, the spinning

mechanism being shown in a raised position;

Fig. 8 is a similar view showing the spinning mechanism in operative position; and

Fig. 9 shows an end elevation of the candy with the wrapping paper about the candy after the spinning mechanism is disengaged from the candy.

Referring to the drawings, particularly to Fig. 1, 10 is the paper roll supported to revolve on a suitable core 11, the bearings for which are not shown. The paper from the roll is guided through feeding pressure rolls 12, both of which rolls receives an intermittent rotary movement in one direction only through a ratchet and gear mechanism 13 actuated from a crank pin 14. This arrangement, therefore, will intermittently advance a predetermined length of the paper through a shearing device 15 through which the paper is fed after it has passed the feeding rolls 12. The shearing device is operable intermittently by a face cam 16 (see Fig. 2). The cam 16 and the gear mechanism 13 are so synchronized that the shears will operate when the feeding of paper through the rolls is interrupted.

The shearing device 15 is supported to bring the end of the paper between the free end of an arm 17 and a track 18. The free end 19 of the arm 17 is enlarged to a width substantially equal to the width of the candy. This end carries wires 19' extending toward the track and which form a support for the end of the paper fed in front of the track 18. A platform 20 alines with the top of the end 19 of the arm 17. This end supports the candy 22 while the same is moved into the track. The platform 20 alines with the conveyor 21 which brings the candy on the platform.

The platform 20 alines also with the stationary bottom 23 of the track 18. The top of the track is made in yielding sections 24 and 25. The section 24 has a raised portion 26 between the ends adapted to form a bearing for candies 22 when the same are forced into the track by a push bar 27. The push bar is supported in front of the platform 20 on a standard 28 which is slidably mounted on a stationary guide 29 of the mechanism. The standard 28 is connected by a

rod 30 to a slide 31 which carries a fork 32 for advancing or removing the wrapped candies from the track to the wheel 33 which cooperates with the gumming device, not shown. The slide 31 is supported by a movable guide 34 which is raised and lowered by means of bell cranks 35 connected by a bar 36, the bell cranks being actuated from a grooved cam 37, the slide 31 being also actuated from a grooved cam 38 through the medium of bell cranks 39 connected by a rod 40. The two grooved cams 37 and 38 are synchronized, so that while the slide is in operation the guide is stationary, and vice versa. The standard 28 being connected to the slide 31 is therefore operable when the slide is operated. The upward movement of the guide and therefore of the slide therewith does not produce any appreciable movement of the standard 28 and therefore of the push bar 27. This upward movement of the guide brings the fork 32 above the bottom 23 of the track (see Fig. 3). The slide 31 is then pulled rearwardly carrying therewith the push bar which will shove the candies 22 on the platform 20, while the fork will move the candies in the track and out of same, as indicated in dotted lines in Fig. 3. The arm 17 has an extension 41 which rests on a roller 42 carried by the bed of the standard and on which the extension 41 is adapted to ride. The extension has an incline 43 which is adapted to be engaged by the roller 42 when the standard is moved rearwardly with the slide, as previously stated. In consequence the arm 17 is swung toward the roller 18 as the push bar moves toward the candies 22. The incline 43 is so related to the roller 42 that the same begins to engage the incline at the moment the push bar 27 brings the candies 22 on to the end 19 of the arm 17; therefore, the candies, arm and push bar move in unison, the lever supporting the candies in the gap. The incline 43 is sufficiently long to bring the arm to the track and maintain it thereat while the push bar moves the candies 22 into the bearing 26 of the track. Since the end of the wrapping paper is located between the end of the arm 17 and track 18, the paper will be engaged by the candy in its movement into the track. The shearing device severs a section of the wrapping paper when the candy enters the track, therefore, the candy 22 enters the track 18 with the wrapping paper. In consequence, the paper is folded by the track about the candy moved thereinto, the yielding section 24 of the track causing sufficient friction between the paper and the track to cause the paper to be dragged out from between the roller 18 and the end 19 of the arm (see Fig. 7) and push it with the candy until the bearing in the track is reached. In

consequence, the wrapping paper is folded 65 about the candy near to one end of said wrapping paper.

The shorter end of the wrapping paper is then tucked or folded against the candy by fingers 44 mounted at one end of a lever 45 which is pivoted between the ends, and the other end of which lever is actuated by a cam 46. The fingers 44 complement the bearing formed by the raised portion 26 in the upper section of the track 24 in which 70 the candy with the paper folded about it can be rotated or spun by means of a pair of endless belts 47 provided above and below the track. The cam 46 is timed so as to swing the lever 45 to bring the fingers 44 80 against the candy brought into the bearing 26 of the track after the push bar 27 begins to retract.

Endless belts are driven by pulleys 48 each constrained to revolve with a shaft 49. 85 Each shaft bears in a corresponding sleeve 50 (see Figs. 4, 5 and 6). Each sleeve has an arm 51 adjacent the pulley extending along the endless belt and carrying at the free end a guiding pulley 52 for the endless 90 belt. The other end of each sleeve carries a head 53, the two heads having interengaging toothed sections 54 the purpose of which will appear hereinafter. The sleeves are supported in the frame structure 55 of the 95 mechanism.

The oscillation of the sleeves 50 in their bearing is controlled by a groove cam 56 which actuates a lever 57 pivoted between its ends and which is in turn connected by 100 a link 57' to one of the heads 53. The bottom 23 and the section 24 of the track are cut out to allow the endless belts to protrude therethrough to come into engagement with the candies 22 in the track. To 105 increase the contact between the belts and the candies we provide an idler 58 within each belt between the driving pulleys 48 and the guiding pulleys 52. The belts are rotated intermittently from a toothed sector 110 59 which meshes with a gear 60 revolubly mounted on one of the shafts 49. The same shaft carries a ratchet 61 constrained to revolve with the shaft and which is engaged by a spring-actuated pawl 62 carried by a 115 plate 63 which is rigid with the gear 60. Each of the shafts 49 carries a pinion 64 constrained to revolve with the corresponding shaft, the two pinions being geared by an idler pinion 65.

The sector 59 is oscillated through the medium of a rod 66 which engages a groove cam 67. The pawl and ratchet mechanism will transmit the oscillating motion of the sector into the intermittent rotary motion 125 of the shafts and, therefore, of the driving pulleys 48, as indicated by the arrows in Fig. 8.

The cam 56 is so timed as to move the two arms 50 toward one another to grip the candy therebetween before the cam 46 has brought the fingers 44 against the candy in the track. The movement of the arms by the cam 56 brings the belts through the cutouts in the track against the candy supported by the bearing formed in the track and the fingers 44. This engagement of the 10 belts with the candy is maintained so by the cam 56 until the candy has been spun or revolved on its axis by the belts 47 by the oscillation of the sector 59. the motion of which is timed by the cam 67.

15 The displacement of the belts 47 is only sufficient to wrap the candy in the paper by leaving one end of the paper so that the same could be pasted subsequently. Before the guide 34 is raised the cam 56 parts the 20 arms 50 and thereby releases the grip of the belts on the candy and leaves the candy wrapped with the paper under the pressure of the yielding section 24. After the guide has been raised to bring the fork 32 to the 25 candy in the track, the cam 38 actuates the slide 31 and moves the wrapped candy from the section 24 to the section 25 (see Fig. 3), and the candy that was in section 25 is moved out of the track to the wheel 33. It 30 will be noted that the unwinding of the paper is prevented by the frictional engagement of the track with the candy that is shoved in the track.

While the disclosure refers to the wrapping of candy, it is self-evident that the machine can be employed for wrapping any articles of approximately cylindrical form and, therefore, we do not wish to be limited to the wrapping of candy only.

40 We claim:

1. In a candy wrapping mechanism, means for presenting a candy with wrapping paper folded against part of the circumference thereof, a swinging tucker arm for 45 bringing one end of the wrapping paper against the candy, and a pair of traveling belts for spinning the candy with the wrapping paper thereon whereby the wrapping paper is wrapped about the candy.

50 2. In a candy wrapping mechanism, a yielding track formed with a candy receiving socket, means for feeding wrapping paper transversely of said track, means for feeding a candy against said wrapping paper and into the track with part of the wrapping paper folded against part of the circumference of the candy, a reciprocating tucker arm for pressing one end of the wrapping paper against the candy, and 55 means for spinning the candy while in said socket whereby the wrapping paper is wrapped about the candy.

60 3. In a candy wrapping mechanism, a track, means for moving a candy into the

track, means for presenting wrapping paper 65 between the candy and the track so that as the candy is forced into said track it will drag said paper into the track with part thereof folded against part of the circumference of the candy, means for bringing 70 one end of the wrapping paper against the candy, and a pair of traveling belts for revolving the candy about its axis whereby the wrapping paper is wrapped about the candy.

75

4. In a candy-wrapping mechanism, a yielding track having a bearing for a candy, means for presenting into said bearing a candy with a wrapping paper folded against a part of its circumference, means for folding 80 one end of the wrapping paper against the candy and adapted to complement the bearing in the track, and means for revolving the candy in the bearing whereby the wrapping paper is rolled about the candy.

5. In a candy wrapping mechanism, a track, means for moving a candy in the track, means for presenting wrapping paper between the candy and the track, a pusher bar for forcing the candy against said paper 90 between the ends of the paper, said pusher bar being adapted to push the candy into said track with the paper folded against a part of the circumference thereof, and a pair of traveling belts for spinning the 95 candy and wrapping paper after the same have been moved into the track.

6. In a candy-wrapping mechanism, a pair of relatively movable arms, means for bringing said arms together and apart, 100 means for feeding candies with the wrapping paper folded against a part of the circumference of the candies between said arms, and a pair of spinning belts carried by said arms for engaging the candies with the 105 paper folded thereon, the movement of said arms toward one another bringing said spinning means into engagement with the candies.

7. In a candy wrapping mechanism, a 110 pair of relatively movable arms, spinning belts carried by said arms, said belts moving substantially at right angles to the movement of said arms, means for moving said spinning belts intermittently, means 115 for moving said arms toward and from one another, said last mentioned means including a pair of cams, and a plurality of bell crank levers, and means for feeding candies with paper folded against a part of the circumference thereof between said spinning belts, the movement of said arms together bringing the spinning belts into engagement with the candies.

120 8. In a candy-wrapping mechanism, a 125 yielding track, means for moving candies into the track, means for presenting wrapping paper and candies on the track so that

the paper is dragged into the track by the candies moving thereinto, means for bringing one end of the wrapping paper against the candy, endless belts mounted to swing in and out of the track to come into engagement with the candies in the track, means for revolving the belts whereby the candies are wrapped with the paper, and means for feeding the wrapped candies out of the track.

9. In a candy-wrapping mechanism, a pair of arms having meshing toothed sections, means for moving one of said arms whereby the other arm may be moved to and from the first arm, endless belts carried by said arms, means for bringing a candy with a paper folded against a part of the circumference of the candy between said belts when the arms are separated, the movement of said arms toward one another bringing said belts into engagement with the candy, bearing means for said candy, and means for imparting a predetermined movement to said belts whereby the candy is spun in the bearing causing the paper to be wrapped about the candy.

10. In a candy-wrapping mechanism, a yielding track, means for moving candies into the track, means for presenting wrapping paper between the candies and the track so that the paper is dragged into the track by the candy moving thereinto, an arm having fingers adapted to engage the candies in the track, said fingers being adapted to bring one end of the wrapping paper against the candy and also form a bearing for said candy, and means for revolving the candy in the bearing.

11. In a candy-wrapping mechanism, a yielding track having a bearing for a candy, means for moving candies through the track into the bearing, means for presenting wrapping paper between the candy and the track so that the paper is dragged into the track by the candy moving therein, an arm having fingers, means for moving the arm whereby the fingers are brought against the candy, said fingers being adapted to fold one end of the paper against the candy and form an additional bearing support for the candy in the track, and means for revolving the candy in the bearing.

12. In a candy-wrapping mechanism, a track having a yielding section, said yielding section having a bearing for candy, means for moving candies into the track, means for presenting wrapping paper between the candies and the track so that the paper is dragged into the track by the candy moving thereinto, an arm having fingers, means for actuating the arm whereby the fingers may be brought against the candy to fold one end of the paper against the candy, said fingers forming an additional

bearing for said candy in the track, and means for revolving the candy in the bearing.

13. In a candy wrapping mechanism, a track having upper and lower members, a pair of facing endless belts, means for moving a wrapping paper in front of said track so that the paper will be at right angles to the track, a pusher bar for moving a candy into said track between the belts, said candy in its movement dragging said wrapping paper therewith, said wrapping paper being folded against a part of the circumference of said candy, bearing means for the candy, and means for revolving the facing surfaces of the two endless belts in opposite directions whereby the candy is revolved in said bearing means.

14. In a candy-wrapping mechanism, a yielding track having a bearing for a candy, means for presenting one end of wrapping paper to the track, means for retaining said end of paper at the track, means for severing the paper, means for feeding a candy into the track against the end section of the paper whereby the paper is dragged into the track by the candy moving thereinto, the frictional engagement of the track with the paper causing the paper at one end to fold against a part of the circumference of the candy with both ends free, means for folding one end of paper against the candy, said means being adapted to form an additional bearing for the candy in the track, and means for revolving the candy in the bearing for folding the opposite end around the candy.

15. In a candy-wrapping mechanism, a pair of facing endless belts, means for presenting a candy with a paper folded about the candy between said belts, bearing means for the candy, and means for revolving the facing surfaces of the two endless belts in opposite directions whereby the candy is revolved in the bearing of said belts.

16. In a candy-wrapping mechanism, a pair of endless belts, an arm carrying each of the belts, means for oscillating the arms in unison whereby the belts may be moved to or from one another, a pawl and ratchet mechanism associated with said belts for moving said belts intermittently in the same direction and so that the facing sides of the pair of endless belts move in opposite directions, means for presenting a candy with a paper folded against a part of the circumference of the candy between said belts, bearing means for engaging a candy and wherein said candy may be revolved by said belts, and means for moving the candy after the same has been revolved out of the bearing means.

17. In a wrapping mechanism for candy, a pair of arms each mounted to oscillate,

said arms having meshing teeth sections, means for moving one of said arms whereby the other arm is moved and whereby said arms may be moved to and from one another, an endless belt carried by each of the arms, driving means for said belts carried by the arms, motion-transmission means between the driving means to move the two endless belts in opposite directions, 10 means for imparting an intermittent motion

in the same direction to the transmission means, bearing means between the endless belts, means for advancing a candy with the paper folded against a part of the circumference of the candy into said bearing 15 means, and means for removing the candy from the bearing means.

MILFORD BERRIAN FERGUSON.
EDWARD HAAS.
